UNITED STATES PATENT OFFICE.

JAMES NEWTON EDWARDS, OF SKIATOOK, OKLAHOMA.

PUMP-JACK.

1,392,310.

Specification of Letters Patent.

Patented Oct. 4, 1921.

Application filed June 17, 1919, Serial No. 304,764. Renewed August 17, 1921. Serial No. 493,094.

To all whom it may concern:

Be it known that I, JAMES NEWTON EDWARDS, a citizen of the United States, residing at Skiatook, in the county of Tulsa, 5 State of Oklahoma, have invented a new and useful Pump-Jack; and I do hereby declare the following to be a full, clear, and exact description of the invention, such as will enable others skilled in the art to which 10 it appertains to make and use the same.

The invention relates to pump jacks, and has for its object to provide a pump jack, particularly adapted for use in oil wells and so constructed that a series of jacks 15 may be connected, by cable to the same source of power, preferably an engine and all of the pump jacks simultaneously operated. Also to provide a pump jack wherein the greatest efficiency of leverage is attained, 20 at the same time providing a jack wherein the parts are reduced to a minimum and the jack as a whole can be constructed at a minimum cost.

A further object is to provide an oil pump 25 jack of the walking beam type, wherein one end of said walking beam is pivotally secured to a polishing rod or pump rod, the other end of said walking beam having a link connection to one arm of a pivoted right 30 angle lever, and means connected to the other arm of said right angle lever whereby the same may be oscillated as desired. Also to provide a safety means whereby if the polishing rod should break the upward 35 movement of the beam will be limited thereby preventing a great deal of work in restoring the same to normal position, or if the operating cable connected to the pivoted right angle lever should break the movement 40 thereof will be limited.

With the above and other objects in view the invention resides in the combination and arrangement of parts as hereinafter set forth, shown in the drawings, described and 45 claimed, it being understood that changes in the precise embodiment of the invention may be made within the scope of what is claimed without departing from the spirit of the invention.

50 In the drawings:—

Figure 1 is a side elevation of the pump jack.

Fig. 2 is a longitudinal section view through the same.

55 Fig. 3 is a top plan view of the jack.

Fig. 4 is a sectional view taken on line 4—4 of Fig. 1.

Referring to the drawings, the numeral 1 designates a base, which base comprises the longitudinal beams 2. Secured to said beams as at 3 are upwardly extending standards 4, the upper ends of said standards being secured to bearing blocks 5. A walking beam 6 is provided, said walking beam 6 having centrally disposed thereon pintles 7, 60 which pintles are rockably mounted in trunnions 8 of the bearing blocks 5. Pivoted and loosely secured as at 9, to one end of the walking beam 6 is the polishing rod 10, 65 which extends downwardly into the casing 11 of the oil wells. Secured to the end 12 of the walking beam is a notch block 13, said notch in said block being adapted to receive transverse portion 14 of the connecting loop 15, lower transverse bar 16 of 70 said loop 15 being disposed in a notch 17 of the arm 18 of a right angle lever 19, said right angle lever being pivotally mounted on a pin 20 which pin is supported in bearings 21 carried by the base pieces 2. Arm 80 22 of the right angle lever extends upwardly and is provided at its upper end with a wear plate 23, said wear plate having a series of transversely disposed notches 24, which notches are adapted to receive the transverse 85 portion 25 of a link 26. Secured to the link 26 as at 27 is a cable 28 which cable may lead and be connected to several other pumps and be connected to an engine whereby an oscillating pull may be imparted to the same, 90 which oscillating pull will cause the angle lever 19 to oscillate on its pivotal point 20 which oscillation will cause a pull to be imparted to the link 15 in a downward direction. The upper end of link 15 being in 95 engagement with the end 12 of the walking beam 6 will cause an oscillation to be imparted to the same, the weight of the polishing rod causing the oscillation in one direction.

A link 29 passes over the end 12 of the walking beam 6 and has its transverse portion 30 disposed in a notch 31, the lower end of said link 29 having disposed therein 100 the upper end of the arm 22 of the angle lever, and so positioned therein that the transverse portion 32 will be below the shoulder 33 of the plate 23 a considerable distance, that is a distance to allow the free 105 oscillation of the pivoted lever 19, however 110

if the cable should break the transverse portion 32 would come into engagement with the shoulder 33 and limit the pivotal action of the angle lever 19, this pivotal action being caused by the weight of the polishing rod 10.

It will be seen that a pumping jack is provided wherein a maximum of leverage is attained, and one wherein it will be impossible for the end of the walking beam to get beyond control.

The invention having been set forth what is claimed as new and useful is:—

1. A pump jack comprising a base member, a standard extending upwardly from said base member, a walking beam pivotally mounted in the upper end of said standard, one end of said walking beam having means whereby the same may be attached to a polishing rod, the other end of said walking beam having a link connection with the end of one arm of a right angle lever, said lever being pivotally mounted on the base, means connected to the end of the other arm 25 of the pivoted right angle lever, whereby said lever may be oscillated and a rocking motion imparted to the walking beam and a link loop pivoted to one end of the walking beam and having its lower end arching the upwardly extending arm of the angle lever, in which loop said upwardly extending arm moves and a limiting stop carried by the upper end of the upwardly extending arm and adapted to be engaged by the

loop when power is removed from the oscillating pivoted right angle lever.

2. A pump jack comprising a base member, a standard extending upwardly from said base member, a walking beam pivotally mounted in the upper end of said standard, one end of said walking beam having means whereby the same may be attached to a polishing rod, the other end of said walking beam having a link connection with an end of a horizontal arm of a pivoted member, 45 said pivotal member having an upwardly extending arm, means connected to the upper end of the upwardly extending arm for operating the pivoted member as a whole, a looped member having its lower end disposed over the upwardly extending arm and its other end detachably and pivotally secured to the walking beam, said looped member extending upwardly and outwardly, a stop carried by the upwardly extending arm 50 and disposed above the transverse portion of the looped member, said stop forming means for engaging the looped member and limiting the inward movement of the upwardly extending arm when the pivoted member is released.

In testimony whereof I have signed my name to this specification in the presence of two subscribing witnesses.

JAMES NEWTON EDWARDS.
